UNITED STATES PATENT OFFICE.

JOHN MURRAY, OF EDINBURGH, SCOTLAND.

BOOK-GLUING MACHINE.

1,177,351.

Specification of Letters Patent.

Patented Mar. 28, 1916.

Application filed October 21, 1914. Serial No. 867,871.

To all whom it may concern:

Be it known that I, JOHN MURRAY, a subject of the King of Great Britain and Ireland, and a resident of Edinburgh, Scotland, have invented a certain new and useful Book-Gluing Machine, of which the following is the specification.

The invention has for its object to provide a simple and effective machine for 10 eccentricating the backs of books before they are bound with glue or other adhesive, and particularly for performing that preliminary gluing done to secure the backs of the successive signatures forming the book. And 15 it comprises improved mechanism for handling the books, and also improved means for distributing the adhesive.

In order that the invention and the manner of performing the same may be properly understood, there are hereunto appended three sheets of explanatory drawings in which—

Figure 1 Sheet 1 is a longitudinal elevation and Fig. 2 Sheet 2 a plan, while Fig. 3 25 Sheet 3 is an end elevation and Fig. 4 a similar view, partly in section, from the opposite end of the machine, of an example of a machine made according to the invention, Fig. 5 being an elevation partly in section, 30 and Fig. 6 an end view of the gluing roller drawn to an enlarged scale.

As shown in the drawings the machine is built up with two side frames A carrying at their one end a table A¹ which has a platform A² beyond its outer end upon which the books are assembled. Beyond the platform and nearer the center of the machine, the table A¹ is gapped along its center. At each side of the gap, rails A³ are provided 40 to support the books near their ends. Near the end of the gap in the table A¹ a second set of rails A⁴ is arranged which divide the back of the books as it were into three parts. At each side of the table A¹ there is provided 45 a vertically and longitudinally arranged flexible conveyer band B of link-belt form faced with rubber or other elastic material. The bands B engage sprocket wheels B¹ arranged at opposite ends of the machine and carried on vertical spindles B² journaled in brackets B³, B⁴. The brackets B³ at the table end of the machine are guided in guides B⁵ in the table A¹, and are engaged by a right and left hand screwed spindle C

mounted transversely to the table. The 55 brackets B⁴ at the opposite end of the machine are carried by a similar spindle C¹ which has on it a handwheel C². The spindles C, C¹ carry sprocket wheels C³ interconnected by a sprocket chain C⁴. The rear 60 pair of the sprocket spindles B² carry wormwheels D engaged by worms D¹ slidably keyed on a transverse shaft D² and held in engagement with the wormwheels by depending lugs D³ secured on the lower part 65 of the brackets and arranged one on either side of the worms D¹. The transverse shaft D² is operated by chain and sprocket gearing D⁴ from a motor D⁵.

Beneath the rails A⁴ is arranged an adhesive applying roll E. As shown in Figs. 4 and 5, this roll is made in three parts which are so spaced as to leave a circumferential gap between each part. In order that the adhesive be properly distributed, it 75 is necessary that the distributing roll be elastic and at the same time resilient. To attain this, the roll E is made of soft rubber, and is pierced longitudinally with two series of circular apertures E². End disks E⁴ are applied to it to close up the ends of the apertures E². The roll E is so positioned beneath the rails A⁴ that the latter pass between the parts through the circumferential gaps formed in it. The roll E is 80 carried on a transverse shaft F journaled at its ends on the one end of a pair of levers F¹ pivoted at their centers on brackets F² carried on the side frames A. The other 85 ends of the levers F¹ are attached to the upper ends of springs F³, the lower ends of which are secured to arms F⁴ extending out from the brackets F². The roll E is served with adhesive from doctor rolls G, G¹ fed from an adhesive supplying tank G². The 90 intermediate roll G is carried in eccentric bushes H in the brackets F², so that it may be adjusted to bear evenly on both the roll E and the doctor roll G¹, a handle J secured on a transverse shaft J¹ being provided by 95 means of which the position of the adhesive tank G² may be adjusted through the linkage J². The roll E is driven through a 100 train of gearing K, sprocket wheels K¹, and a sprocket chain K², from the motor D⁵. 105

In operation, the conveyer bands B are adjusted by means of the right and left hand screwed spindles C, C¹ until they are such

a width apart as to suit the length of the books being glued. The books, which are arranged on the platform A² in batches transversely with their backs downward, are 5 presented between the bands B. The bands seize them and traverse them along the rails A³ on to the second set of rails A⁴ and over the adhesive applying roll E. They are finally delivered on to that part of the rails 10 A⁴ which extends out rearwardly from the machine to carry them. The roll E as hereinbefore described is circumferentially gapped, so that no adhesive is applied to that part of the books which travel along the 15 rails A⁴. The pressure with which the roll E bears on the back of the books is adjustable by means of the springs F³, so that the adhesive may be adequately distributed. The roll G is also adjustable in the eccentric 20 bushes H, so that it can be made to bear evenly on both the roll E (when this roll is pressed down by the books passing over it) and on the doctor roll G¹, thus distributing the adhesive on to the roll E in an even layer 25 and regulating the supply of adhesive between the rollers G¹ and E.

What I claim is:—

1. In a book gluing machine for the purposes set forth, supporting means on which 30 the backs of the books in edge position rest, traveling means engaging the opposite ends of the books to move the latter through the machine on said supporting means, and means for applying adhesive to the backs of 35 the books during said travel, substantially as described.

2. In a book gluing machine for the purposes set forth; a table gapped along its center, a platform on one end of the table, 40 conveyer bands adjustable as to the width they are apart, rails upon which the books are carried, means for applying the adhesive to the backs of the books, and means for driving the conveyer bands.

45 3. In a book gluing machine for the purposes set forth; a table gapped along its center, a platform on one end of the table, conveyer bands adjustable as to the width they are apart, rails upon which the books 50 are carried, an adhesive applying roll journaled beneath the rails, means for feeding the adhesive roll, and means for driving the

conveyer bands and the adhesive applying roll.

4. In a book gluing machine for the purposes set forth; a table gapped along its center, a platform on one end of the table, conveyer bands, sprocket wheels at each end of the machine engaging the conveyer bands, vertical spindles journaled in brackets carrying the sprocket wheels, right and left hand screwed spindles engaging the brackets, gearing between the screwed spindles and between these spindles and a first motion shaft, rails upon which the books are carried, an adhesive applying roll journaled beneath the rails, means for feeding the adhesive roll and means for driving the adhesive applying roll.

5. In a book gluing machine for the purposes set forth; a table gapped along its center, a platform on one end of the table, conveyer bands adjustable as to the width they are apart, rails upon which the books are carried, an adhesive applying roll circumferentially gapped and having circular longitudinal apertures and ends disks of soft rubber closing the ends, means for feeding the adhesive roll, and means for driving the conveyer bands and the adhesive applying roll.

6. In a book gluing machine for the purposes set forth; a table gapped along its center, a platform on one end of the table, conveyer bands adjustable as to the width they are apart, rails upon which the books are carried, an adhesive applying roll journaled beneath the rails, spring-controlled hinged levers carrying the adhesive applying roll, an adjustable adhesive supplying tank, a doctor roll fed from the supply tank, an intermediate roll between the doctor roll and the adhesive applying roll, eccentric bushes in which the intermediate roll is carried, and means for driving the conveyer bands and the adhesive applying roll.

In testimony whereof I have signed my name to this specification, in the presence of two subscribing witnesses.

JOHN MURRAY.
